UNITED STATES PATENT OFFICE.

ROBERT E. L. JANNEY, OF CHICAGO, ILLINOIS, ASSIGNOR TO AMERICAN STEEL
FOUNDRIES, OF NEW YORK, N. Y., A CORPORATION OF NEW JERSEY.

POCKET-COUPING.

1,181,386.

Specification of Letters Patent.

Patented May 2, 1916.

Application filed August 26, 1915. Serial No. 47,406.

To all whom it may concern:

Be it known that I, ROBERT E. L. JANNEY, a citizen of the United States, and resident of Chicago, in the county of Cook and State of Illinois, have invented certain new and useful Improvements in Pocket-Couplings, of which the following is a specification.

My invention relates to car couplers, and has particular reference to a novel means 10 for adjusting the height of pocket couplers.

It is common to provide the pockets which are attached to the end sills of locomotives, or cars, with a shelf projecting laterally from the pocket and adapted to 15 underlie and support the coupler which is mounted in the pocket, the intention being that a portion of the weight of the coupler shall be supported independently of the pivot. It has been found, however, that the 20 wear incident to service permits downward tilting of the coupler; this tilting finally reaching a point beyond the permissible limits. Means are therefore commonly provided for raising the coupler to its correct 25 height, and my invention is particularly directed to such means as will enable the use of simple devices for raising the coupler to its required height.

The invention will be more readily understood by reference to the accompanying 30 drawings, wherein—

Figure 1 is a plan view of a coupler pocket and a coupler mounted therein, my improvement being applied thereto; Fig. 2 is a side elevation of the construction shown 35 in Fig. 1; Fig. 3 is a plan view of the tray which cooperates with the pocket and coupler, and Fig. 4 is an edge elevation of the tray.

Referring more particularly to the drawings, it will be seen that I provide a pocket 40, having a flared side opening within 10, having a pivot pin 11 seated. A coupler 12 is provided with a short shank 13, which 45 seats in the recess and is engaged by the pin. The coupler is adapted for horizontal swinging movement with the pin as a center. The pocket 10 is provided with a horizontal shelf 14, which underlies the coupler 50 and is adapted to be engaged by the lower portion 15 thereof, this shelf acting as an auxiliary support for the head of the coupler.

My improvement consists in the application of a tray, consisting of a flat plate 16, 55 having upstanding flanges 17, which are interrupted at one side to permit the tray to engage the lower portion 15 of the coupler. After having been applied, as shown in Fig. 2, it will be seen that the tray cannot escape, being held in place by the weight of the coupler and adapted to slide horizontally with the coupler. The tray itself may serve as a means for restoring the coupler to its proper position after it has begun to 60 tilt, and any further tilting may be overcome by inserting one or more shims, such as shown at 18, in Fig. 4, in the tray. These shims may be of any desired shape and if they are of sufficient length to lie within the 65 vertical flanges 17 of the tray, they cannot escape therefrom. The shims may be constructed of any waste pieces of sheets or plates which may be found in railroad yards.

It will be seen that the improvement 70 adapts itself for general use without expense and provides a simple and economical means for maintaining the coupler at its required height.

I claim:

1. In a device of the class described, the combination of a pocket having a shelf, a coupler mounted in the pocket and overlying said shelf, and a flanged tray engaging 85 the shelf and pocket and serving as a means for adjusting the height of the coupler, substantially as described.

2. In a device of the class described, the combination of a coupler pocket provided with a horizontally projecting shelf, a short 90 shank coupler mounted in the pocket, the head of the coupler overlying said shelf, and a flanged plate engaging the foot of the coupler and adapted for sliding movement on said shelf, and shims held within 95 said flanged plate and serving to adjust the height of the coupler, substantially as described.

Signed at Chicago, Illinois, this 21st day of August, A. D. 1915.

ROBERT E. L. JANNEY.
